UNITED STATES PATENT OFFICE

2,053,126

POWER TUBE ANODE

Jetson O. Bentley, Castle Point, N. Y., assignor to
General Electric Company, a corporation of
New York

Application September 19, 1931, Serial No. 563,850

11 Claims. (Cl. 250—27.5)

The present invention relates to electron discharge devices of the power type and more especially to their electrode construction.

One of the most difficult problems encountered in power tube design is that of the anode construction on account of the fact that this member is called upon to dissipate large amounts of heat energy from a relatively small surface. The problem is accentuated in the case of tube design necessitating a flat anode of thin material, operated at relatively high temperature and in which the distances between the anode and adjacent electrodes are relatively small in order to obtain the desired operating characteristics. The slightest warp or distortion of the anode under these conditions causes objectionable deviations in the tube characteristics and inasmuch as the distortion usually becomes worse after long service of the anode, the latter may in time contact with the adjacent electrode and cause a short circuit.

One of the objects of the present invention is to provide an improved anode construction for power tubes which will not bow, warp or distort in any manner when subjected to heat, under operating conditions. A more general object is to improve the construction and operation of power tubes with the view toward maintaining their electrical characteristics substantially constant.

In the past, it has been customary to meet the problem of anode distortion, by which term, I mean relative changes in space of any portion of the member, whether due to warping, bowing or otherwise, by rigidly bracing the electrode in a heavy frame. The idea underlying this prior art design was to offer equal and opposite forces to those exercised by the expanding member. However, this form of construction has not been altogether satisfactory, particularly in those cases where the anode material is relatively thin and of extensive area. Accordingly, I propose an improvement of design which may be used quite generally for electrode construction but which is especially desirable in the case of flat anodes of thin stock, employed in connection with small inter-electrode spaces. The principle of operation which I employ in accordance with the present invention differs from that of the prior art in that practically all parts of the improved anode are given free and unhampered opportunity to expand with the changes of temperature, the freedom of movement being afforded without causing any change in the operating characteristics of the tube.

In carrying out the invention, I divide the

anode into a number of sections which are held in a frame in such a manner that they may expand freely in all directions when heated. In addition to allowing free expansion, the improved construction lends the further advantage of effecting a substantial saving of anode material, since the sections may be salvaged from other tubes, or may be cut in an economical manner from the raw sheet stock. The sections may also be made of much lighter material than the prior art anodes, which not only tends to reduce the cost of material but also facilitates the ease with which the material is worked.

The invention will be better understood when reference is made to the following description and the accompanying drawing in which Fig. 1 shows a tube in elevation containing an anode improved in accordance with my invention; Fig. 2 is a perspective view of the improved anode, in partly disassembled form; Fig. 3 is an enlarged view of a corner portion of the assembled anode, Fig. 4 is a cross-section taken along line 4—4 of Fig. 3; while Figs. 5, 6 and 7 show modified forms of slats which in their assembled form may constitute the active portion of an anode.

Referring to Fig. 1, numeral 1 designates the envelope of a highly evacuated tube containing a filamentary cathode 2, an electrostatic control member 3 and a rectangular anode 4, closely surrounding the control member. As will be seen from the illustration, the electrodes have relatively large active areas and the inter-electrode spaces are relatively small in order to obtain the proper operating characteristics. The envelope terminates in a pair of oppositely directed stems 30 to which are secured clamp members 5 for supporting the electrode structure in the usual manner. Inasmuch as the electrode supporting structure and the relative arrangement of the electrodes are well known in the art, it is unnecessary to present a detailed description other than to state that in tubes of this character, it is essential that the anode shall remain free from warping, bowing or other form of distortion in order that the device may efficiently translate electrical energy. When a tube of this sort is provided with an anode of the prior art design, the active surface of which ordinarily is made of sheet metal in one piece, there is a tendency for the center of the anode, which usually is the 50 hotter portion, to bow in toward the control member under the influence of heat employed during exhaust or generated by the filament and load currents in operation. In order to preclude this deformation of shape, it has been proposed 55

heretofore to provide the anode with strengthening ribs or fins which extend over the central part of the anode so as to offer a restraining force to this bowing effect. Sometimes the prior art anode would warp from corner to corner and change the line-up between the electrodes. An anode, improved in accordance with the present invention, positively avoids these bowing and warping effects without necessitating ribs, fins or other strengthening members.

I propose to divide the anode into a number of sections 6, as slats or strips, shown more clearly in Figs. 2 and 5, arranged side by side, in edge-wise relation so as to form a continuous surface, 5 also secured together in a flexible manner by a frame of relatively light material. These slats may be fabricated of any suitable material and in the case of large power tubes, are usually constituted of molybdenum. I prefer to make this 10 subdivision along the direction of the shorter or transverse dimension of the anode, although it will be understood that I may, if desired, arrange these slats in the longitudinal direction of the anode. The frame consists of two pairs of U 15 shaped side members 7, 8, also preferably of molybdenum, one of each pair, the member 8 as shown, fitting within the other member 7 so as to leave a space between the flange portions which receives the end of each slat nearer thereto, in 20 a sliding fit. The slats may be inserted between both adjacent pairs of the flange portions so that the anode surfaces, designated as a whole by the reference character 9, are arranged in opposed relation, and at such a distance apart 25 as to provide the proper inter-electrode space when assembled in the tube. The side members 7, 8 are held together by means of two adjacent pairs of cross pieces 10, preferably of the same material as the side members, these pieces having 30 a U-shape with flange portions which embrace the upper edges of the two uppermost slats and abut the lower edges of the lowermost slats. The side and cross pieces are secured together at their corners by rivets passing through openings 11, 12 35 and 19 to constitute a rigid frame, as shown complete in Fig. 1.

The dotted line 13 in Fig. 3, indicates the extremity of the slats within the side frame members and it is evident that the distance between 50 the latter when assembled should be somewhat greater than the length of each slat so that the latter can expand freely in its longitudinal direction. If desired, the slats may be reinforced in this direction by one or more fins 14, formed 55 preferably integral with each slat as a single upturned member, shown in Figs. 5 and 7, or several of such members as indicated in Fig. 6, positioned conveniently near one or both of the edges of each slat. The anode structure as a whole may 60 further be strengthened by a rigid U shaped member 15 disposed intermediate the ends of each slat, preferably midway between, and passing through suitably shaped apertures cut in the upturned fin portions. The member 15 is riveted 65 in a pivotal manner as indicated by reference character 16 to each slat and cut away at each end to form a tongue which is inserted under the overhanging portions of the cross-members and riveted thereto. The tongue portion of each 70 member 15 is provided with a slot 17 which registers with a round rivet hole 19 in a cross member so as to allow longitudinal expansion of the member. The middle portion of the latter is heated to a greater extent than the end portions and consequently, there is a temperature 75

difference in the member which necessitates a provision for expansion.

From the foregoing description and the accompanying illustration, it will be evident that the anode slats are free to move in their longitudinal direction along which the greatest expansion in these members takes place. Hence, when the improved anode is subjected to severe heat conditions either in operation or during exhaust, the various metal parts may expand freely without causing distortion, warping or bowing of the electrode, as a whole. It has been found that an electrode construction in which free movement is thus permitted to the constituent parts thereof, lends itself to the proper anode design of all 10 types of tubes but is particularly desirable in those constructions which require the minimum amount of material used for the anode and in which the inter-electrode spaces are extremely 15 small and critical.

What I claim as new and desire to secure by Letters Patent of the United States is:

1. An anode for an electron discharge device comprising a plurality of sections forming a continuous surface, said sections being held in a 25 frame which permits movement of the sections with respect to one another and with respect to the frame when the anode is exposed to heat under operating conditions.

2. An anode for an electron discharge device 30 comprising a plurality of flat rectangular strips arranged side by side in edge-wise relation, said strips being secured at their ends by a frame which permits relative movement of the strips with respect to one another and with the frame 35 when the anode is exposed to heat.

3. An anode for an electron discharge device comprising a pair of opposed rectangular members, each having a dimension greater in one direction than in the other, said members being 40 constituted along the direction of greater dimension, of a plurality of sections which permit relative movement therebetween and thereby preclude distortion in the direction of greater dimension during operation of the anode.

4. An anode for an electron discharge device comprising a plurality of flat rectangular strips arranged side by side in edge-wise relation, a supporting frame for said strips which permits relative movement between the strips, said frame 50 consisting of side and cross members fitted together so as to leave spaces in which the strips are free to move in their longitudinal direction.

5. An anode for an electron discharge device comprising a pair of opposed rectangular members, each having a dimension greater in one direction than in the other, said members being 55 constituted along the direction of greater dimension, of a plurality of sections which permit relative movement therebetween and thereby 60 preclude distortion in the direction of greater dimension during operation of the anode, and a frame for flexibly holding the sections in place.

6. An anode for an electron discharge device comprising a plurality of sections forming a continuous surface, said sections being held in a frame which permits movement of the sections with respect to one another and with respect to the frame when the anode is exposed to heat, each of said sections being provided with a reinforcing upturned portion extending along its 70 length.

7. An anode for an electron discharge device comprising a plurality of sections forming a continuous surface, said sections being held in a 75

frame which permits movement of the sections with respect to one another and with respect to the frame when the anode is exposed to heat, each of said sections being provided with a reinforcing upturned portion extending along its length, a support for said sections positioned intermediate their ends, said upturned portions being cut away to receive said support.

8. An anode for an electron discharge device comprising a pair of opposed rectangular members, each having a dimension greater in one direction than in the other, said members being constituted along the direction of greater dimension, of a plurality of sections which permit relative movement therebetween and thereby preclude distortion in the direction of greater dimension during operation of the anode, and a frame for flexibly holding the sections in place, a support for each of said rectangular members, said support extending in the direction of the greater dimension and pivotally secured to the sections intermediate their length whereby relative movement is permitted between each support and the sections secured thereto.

25 9. An anode for an electron discharge device comprising a pair of opposed rectangular members, each having a dimension greater in one direction than the other, said members being divided along the direction of greater dimension into a plurality of sections which permit relative

movement therebetween, thereby precluding distortion in the direction of the greater dimension during operation of the anode, a frame for holding the sections in place, said frame consisting of side and cross members rigidly secured together at their extremities.

10. An anode for an electron discharge device comprising a pair of opposed rectangular members, each having a dimension greater in one direction than the other, said members being divided along the direction of greater dimension into a plurality of sections which permit relative movement therebetween, thereby precluding distortion in the direction of the greater dimension during operation of the anode, a frame for flexibly holding the sections together, said frame consisting of side and cross members, a support for each of said sections, said support extending in the direction of greater dimension and pivotally secured to the sections at positions intermediate their length whereby relative movement is permitted between the support and the sections secured thereto, said support being secured to the cross members of the frame by flexible joints.

11. An anode for an electron discharge device comprising a plurality of metal sections freely movable with respect to one another under operating conditions.
